UNITED STATES PATENT OFFICE.

CHARLES T. ELLIOTT, OF PHILADELPHIA, PENNSYLVANIA, ASSIGNOR TO H. W. BUTTERWORTH & SONS COMPANY, A CORPORATION OF PENNSYLVANIA.

MACHINE FOR LIXIVIATING TEXTILE FABRICS.

Application filed August 31, 1923. Serial No. 660,313.

To all whom it may concern:

Be it known that I, CHARLES H. ELLIOTT, a citizen of the United States, and resident of Philadelphia, county of Philadelphia, 5 and State of Pennsylvania, have invented an Improvement in Machines for Lixiviating Textile Fabrics, of which the following is a specification.

In treating fabrics with alkaline substances, such as lye or caustic soda, as in mercerizing, the fabric becomes impregnated with the said alkaline substance and must be subjected to a washing operation for removing the same before being subjected to 15 finishing processes, and it is the object of my invention to provide a machine which is specially designed for the purpose of thoroughly lixiviating or washing the fabric during its travel through the machine in a 20 continuous manner, the construction being such that a more satisfactory and rapid elimination of the alkali from the fabric is assured than has been the general practice in machines of this character heretofore in 25 use.

In machines of this class, the fabric is carried through the machine in a vertical zigzag manner, being subjected at its lower bends to washing fluids of graded purity, 30 whereby it leaves the machine after treatment to the fluid of greatest purity, said fabric being subjected to a washing operation in a heated atmosphere as it passes from one body of washing fluid to the next and 35 at the same time to more or less friction for loosening the alkaline content whereby it may be more readily washed out when the fabric passes through the successive stages of the washing operation, and my invention 40 has for an object the provision of adjustable means for varying the amount of the friction applied to the fabric by spiral stretching rolls preliminary to being subjected to the washing and rubbing operation in the heated 45 atmosphere within the chamber of the apparatus, whereby the strain due to this operation may be increased or decreased according to the strength or delicacy of the fabric being treated.

50 My invention also has for an object the special construction of the casing of the machine, and more particularly, for providing the successive stages of the washing fluid whereby great strength and rigidity is insured at a considerable lessened cost than

has heretofore been possible with machines as previously made.

A further object of my invention is to provide means for accurately guiding the selvage edges of the fabric at uniform speeds 60 and at the same time compensate for any changes in linear length to insure a constant and uniform feeding of the fabric as a whole, whereby it is presented to the lixiviating devices in a more satisfactory manner 65 and under more uniform tension.

My object is also to provide the enclosed chamber (in which the washing takes place in a heated atmosphere) with large hinged side doors which expose the interior sufficiently to permit the examination of the 70 fabric content and the means for washing the same, said doors controlling openings arranged considerably above the fluid level in the tank.

75 A further object is the provision of bearings for the guide rollers within the lixiviating chamber having a composition which is self-lubricating, notwithstanding the presence of the alkaline solution or atmosphere.

With the above and other objects in view, the nature of which will be more fully understood from the description hereinafter, the invention consists in the novel construction of machine for lixiviating textile fabrics, as hereinafter more fully described and 85 defined in the claims.

Referring to the drawings: Fig. 1 is a side elevation of a machine for removing alkaline substances from fabrics and embodying my improvements; Fig. 2 is a longitudinal sectional view of the same; Fig. 3 is a vertical transverse section of the same, taken on line 3-3 of Fig. 2; Fig. 4 is a horizontal sectional view of the same, taken 90 on line 4-4 of Fig. 2; Fig. 5 is a side view of one end of the adjustable stretching and rubbing devices showing the means for driving the same; Fig. 6 is a horizontal section of a portion of the machine taken on line 95 6-6 of Fig. 2; and Fig. 7 is a horizontal section showing a portion of the tension controlling means and taken on line 7-7 of Fig. 2.

100 Fig. 2 is a chamber having a cover 37 and a specially constructed lower or tank portion 5. This tank portion comprises a box-like body having side walls 4, end walls 4^a and 4^b and an inclined floor or bottom 3 which inclines upwardly from the end wall 4^b and 110

terminating in the opposite end wall 4^a. The box-like tank thus provided is divided into a plurality of washing compartments 12^a by transverse division walls 6 which are flanged at bottom and ends, as at 7, the same being secured by cap-screws to the inclined bottom 3 and side walls or frames 4 (Figs. 2 and 6). These transverse division walls are all the same height and character and because of the incline of the supporting bottom, their upper edges constitute dams of successive higher levels, so that the fluid supplied to the uppermost compartment 12^a overflows into the next lower compartment, and so on through the series, until it reaches the lowermost compartment or well 12 into which extends the end wall 11 of the chamber 2 to provide a fluid seal. Similarly, the other end wall 13 of the chamber 2 extends down into the uppermost or liquid receiving compartment to form a fluid seal. By means of these fluid seals, the steam or vapor within the chamber 2 and space in the tank portion 5 above the fluid compartments 12^a is prevented from freely escaping and yet provide passages through which the fabric F may freely pass into and out of the said chamber. The washing fluid may be supplied to the uppermost compartment 12^a by a suitable supply pipe such as 14^a when starting the machine and the level desired is maintained in the lowermost compartment or well at 12 by employment of an overflow pipe 14^b preferably of a trap form. During the operation of the machine, the additional water or washing fluid required to be supplied to the uppermost compartment 12^a is furnished by the spray pipe 54^a which sprays the fresh water or fluid directly upon the fabric immediately before passing between the squeeze rolls 26 and 27 to be hereinafter referred to.

Referring more particularly to the construction of the transverse division walls or dams 6, the same each consist of a unitary casting having a front plate 9 and a back plate 8 with a vertical passage 10 between them, the front plate extending to a higher elevation than the back plate to guide the fluid flowing over the back plate into the passage 10 and said passage having an opening at its bottom through the front plate for the flow of the fluid into the next lower compartment 12^a at or near its bottom so as to provide an upward current within the compartment. As the floor 3 upon which the division walls 6 rest is inclined, the lower flanges 7 of the said walls are planed on an incline to correspond, whereby the walls or dams may stand in upright positions (Fig. 2).

Arranged within each of the washing compartments 12^a is a transverse guide roller 15, the same having end journals which are received in bearings 16 extending through

the side walls 4 (Fig. 6) and provided with self-lubricating bearing surfaces, the same composed of a wooden sleeve 16^a saturated or thoroughly impregnated with an oil lubricant. A bearing of this character is constantly presenting fresh lubricating surfaces as it wears and the unexposed body of the fibrous bearing material maintains its lubricating capacity. The bearings 16 are removable from the outside of the machine, so that when new sleeves 16^a are to replace worn ones, this may readily be done.

Arranged in the upper portion of the chamber 2 are a plurality of guide and feeding rollers 17, the same being preferably of larger diameter than the rollers 15 and located above the spaces intermediate of said rollers, so that the fabric F to be treated is guided over the rollers 17 and under the rollers 15 and thereby caused to travel in a vertical zig-zag manner, the successive vertical web portions being preferably parallel (Fig. 2). The fabric F in passing into the chamber 2 is guided in contact with a spiral roller 50 journaled above the well 12 and thence passes under the submerged roller 15^a of the lowermost compartment 12^a, thence upward over the first feeding and guide roller 17, thence downward around the submerged guide roller 15 in the next compartment 12^a and so on, passing alternately about the rollers 17 and 15. After leaving the last of the guide rollers in the uppermost compartment 12^a, the fabric is guided upward through the passage 14 between the wall 13 of chamber 2 and the upward extension of the tank wall 4^a, over a guide 26^a to and between the squeeze rolls 26 and 27 by which the fluid contained in the fabric is largely squeezed out and mixed with the spray water from spray pipe 54^a, returned to the uppermost compartment, as will be readily understood by reference to Fig. 2. The lower squeeze roll 26 is journaled in stationary bearings and is revolved by a large gear wheel 25, driven in turn by a pinion 24 and shaft 22, the latter having a belt wheel 23 by which it may be rotated. The upper squeeze roller 27 is carried in adjustable bearings 30 suitably guided and respectively adjusted by levers 28 respectively hinged at one of their ends and having the other of their ends respectively connected to rods leading down to separately hinged levers 32, weighted at 33. The levers 28 are each provided with an adjusting screw 29 connecting with the adjustable bearings 30. In this manner, the squeeze roller 27 may have the pressure on each end separately adjusted. To raise the squeeze roller 27, I provide a transverse shaft 34 having cams 35 (one for each lever 28) and an operating handle 36. When the parts are in the positions shown in Fig. 1, the full pressure is applied to the roller 27 and the position of the levers 28

are adapted to be simultaneously acted upon by the cams 35 when the operating handle 36 is thrown. By this means, any desired weight may be applied to the roller 27 and each end may operate independently of the other, but when raising the roller for threading in the web or for other reasons, the two ends of the roller may be lifted simultaneously.

10 The chamber 2 is provided with a suitable cover 37 of any suitable construction to seal it at the top for preventing free entrance of the atmosphere and avoiding unrestricted escape of the steam and heated vapors. The 15 cover may be of wood with metal reinforcements and may be clamped in closed position by cross bars 38 and screw clamps 39 hinged to the top of the chamber and cooperating with the cross bars to clamp the 20 cover in position, as will be understood by reference to Figs. 1 and 3. To enable the requisite temperature to be maintained, it is desirable to permit some change in the vapor content of the chamber as when introducing more steam and hot vapors; and with this object in view, I provide vent pipes 40 which, while permitting passage of vapors in volume equivalent to the entering 25 volume of fresh steam and vapors and preventing excessive internal pressure, maintain the chamber to all practical intent a sealed chamber.

Further considering the feeding and guide rollers 17, these are also journaled in bearings 18 having self-lubricating sleeves as in the case of the rollers 15, but in this case one of the journals of each of the rollers 17 is extended through its bearing and is driven from a shaft 20 by mitre gears 19 (Figs. 2 30 and 3), the said shaft 20 being itself driven from shaft 22 by bevel gears 21.

The interior of the chamber 2 is provided with a series of perforated pipes constituting scouring, spray or jet pipes 54 arranged transversely for the purpose of spraying hot steam or vapors against the surface of the fabric being treated and are so positioned that they act upon the fabric on its upward movement after leaving one of the 45 washing compartments 12^a. Some of said spray or jet pipes 54 act upon one surface of the fabric and the others act upon the other surface, so that both surfaces of the fabric are treated in the same manner. 50 These jet pipes 54 are connected to a manifold of any suitable construction to which the heated vapors or steam is supplied by a pipe 54^a having a control valve 54^b (Fig. 1). Arranged above the jet pipes 54, are a series 55 of rubbing bars 55, one to each jet 54, and adapted to act on the opposite side of the fabric being treated; and it is desirable that the bars 55 are so positioned that the fabric rubs gently against them to loosen the alkali-line material which may be present. These

bars 55 may be fixedly positioned, if so desired, but I prefer that they shall have slight adjustment capacity, as shown at 55^a, for example, (comprising a slot and clamping screw), so as to vary the extent or degree 70 of rubbing action of said bars upon the fabric. Any other suitable means of adjustment may be employed. The essential feature is to provide a relative adjustment between the jet or spray pipes 54 and the 75 rubbing bars 55 with respect to a common vertical plane, the said pipes and bars preferably in contact with opposite surfaces of the fabric at all times, whereby the jet pipes also act as rubbing bars. In every case 80 where a jet pipe is employed, the associated rubbing bar is in contact with the opposite surface of the fabric to that being treated by the jets of steam or vapor from the jet pipes. 85

As a preliminary to the proper washing and scouring of the fabric, constituting the lixiviating operation, the fabric should be stretched to proper width so that in passing about the guide and feeding rollers, it is in 90 a smooth condition, and to this end I provide certain improvements for this purpose. The spiral roller 50 before referred to may consist of a roller having one-half of its length formed with a right-hand spiral 95 thread and the other half with a left-hand spiral thread, the spirals so arranged that the drawing of the fabric over the roller will cause it to stretch transversely. In addition to this preliminary stretching, I provide 100 special stretching means for treating the fabric preferably after it has passed through some of the washing fluid. Two spiral rolls 56, between which the fabric passes, are journaled in an adjustable frame comprising 105 two heads 57 connected by heavy bolts or studs 57^a, said frame journaled in the side walls of the chamber 2 for adjustment about a transverse axis passing through the plane of the fabric when traveling between the 110 rollers 15^a and 17 unacted upon by the spiral rolls. The frame and spiral rolls may be adjusted so that the spiral rolls will not touch the fabric, but when adjusting otherwise, the respective rolls may be simultaneously moved into contact with opposite surfaces of the fabric to apply more or less friction and transverse stretching of the same, less pressure and friction being employed with delicate fabrics than where the fabric is strong. The spiral rolls are each made with one-half their length right-handed and the other half left-handed in respect to the spiral grooves and ribs (Figs. 3 and 4), the ribs or teeth being preferably V or angular in shape. The adjacent ends of the two rolls 56 have their spirals cut so that one is right-handed and the other is left-handed, because they rotate in opposite directions. These two spiral rolls 115 120 125 130

are geared together by gears 58 and are rotated by a rotating shaft 61 (concentric with the axis of the adjustable frame 57) and gear 60 thereon meshing with gear 59 on one of the spiral rolls 56 (Fig. 5). The shaft 61 is provided with a sprocket wheel 62 which is driven by a chain drive 64, itself driven from a sprocket wheel 63 on the first guide roller 17 (Figs. 2, 3 and 4). Any other manner of driving the rolls 56 may be employed, if so desired. The frames 57 may be adjusted about its axis for adjusting the relative positions of the spiral rolls and held in adjusted positions by means of the clamping screws 73 and slots 72 (Fig. 5). It will now be understood that when the device is adjusted, as in Figs. 2 and 5, no material action by the spiral rolls 56 is had upon the fabric as there is space between them for the free upward travel of the same. If, however, the frames 57 are adjusted clockwise in Fig. 2, then the uppermost spiral roll 56 is pressed against one side of the fabric and the other or lowermost spiral roll is pressed against the other side of the fabric, with the result that it is caused to take a more or less sinuous course in contact with said rolls and will be spread or stretched transversely from selvage to selvage. In this way, when the fabric reaches the first roller 17, it is already smoothed out and in perfect condition for the lixiviating or washing process which is to follow. The extent of the friction to be applied is determined by the rotary adjustment of the frames 57 and the extent of adjustment is governed by the character of the fabric, frail or lace-like fabrics requiring less friction than goods of heavier and more rigid texture. Experience will guide the operator in charge in such adjustment. While these stretching spiral rolls 56 are not intended to produce the rubbing or scouring action required, nevertheless, since they act upon the fabric after it has passed through the fluid in the well compartment 12, they do perform a preliminary scraping off of alkaline material during the stretching operation; and moreover, as they rotate at a faster surface speed than that of the fabric, their rubbing action is far more pronounced than that of the individual bars 55 and consequently, said spiral rolls perform the dual function of stretching and rubbing.

While access may be had to the chamber 2 by removing the cover 37 therefrom, nevertheless, the presence of the rollers 17 prevent a man from reaching the inner working parts of the chamber and of the tank base 5 and additional means are necessary to provide for such access. To this end, each side of the chambers 2 is provided with large man-holes 65 between the level of the rollers 17 and spray pipes 54 and said holes

are normally closed by large cover plates 66 hinged at their lower parts to the outer side walls of the chamber as at 67, said cover plates each clamped in sealing or closed position by screws 69 extending through a cross bar 68 detachably held in position by lugs 68^a projecting from the side walls of the chamber (Fig. 4). The cover plates are also provided with packing 66^a near their perimeters to insure a tight joint. By means of these manholes, the machine may be threaded with the leading-in-fabric when starting up the machine or for temporary repairs or cleaning when required; and quick access to the interior may be readily had even while the machine is in operation if necessary for any reason.

A steam pipe 70 having a control valve 71 (Fig. 2) may be employed to provide steam to the well 12 to heat the fluid in the first compartment 15^a, so that the fabric may be heated and saturated with hot fluid before entering the chamber 2 and subjected to the spiral rolls 56, it being thus rendered more pliable and responsive to treatments to follow.

While the fabric may be delivered to the lixiviating machine from any source required, it is a customary practice to mercerize the fabric while in the custody of a tentering machine and from such machine delivering it to the lixiviating machine. This is best accomplished by an interposed feeding means shown at the left of Figs. 1 and 2 and which will now be described. 41 are upright guide frames having vertical guide slots 42 in which journal boxes 43 slide, said boxes indirectly carrying a guide roller 44 through the medium of a shaft 53 upon which the roller is journaled with freedom of rotation. The shaft 53 is journaled in the boxes so as to have rotation therein and is also provided near each end with pinions 52 which mesh with racks 51 secured to the upright guides adjacent to the slots 42 thereof (Figs. 2 and 7). In this manner, the roller 44 may be free to rotate at any speed and the supporting rod 53 is caused to remain horizontal at all times in its upward and downward movement. The weight of the roller 44 and associated parts is counter-weighted to the desired extent by the weights 48 and chains 47, which latter are guided over grooved wheel 49 and have their ends connected to the boxes 43. Near the upper end of the frame 41 is journaled a guide roller 45 and opposite to it is a second roller 46 acting both as a guide and feed roller, it being positively rotated by the sprocket chain 64 which has heretofore been referred to as the means for rotating the spiral rolls 56. The fabric F passes over roller 45, thence under the compensating or tension roller 44, thence upward over feed roller 46 and downward to spiral roller 120

50. In this manner, the feed roller 46 feeds the fabric with a speed commensurate with the needs of the lixiviating machine proper. While the press rolls 26 and 27 provide a 5 pull on the fabric, it is not desirable to rely upon them alone for feeding the fabric through the chamber 2 and hence the rollers 17 are employed also as feed rollers; and similarly, it is not desirable for these rollers 10 17 to pull the fabric into the machine against material resistance and hence the feeding roller 46 with the compensating tension roller 44 are provided, the former insuring the delivery of the fabric and the 15 latter insuring a uniform tension. It sometimes happens that the fabric varies in its tendency to stretch according to the density of its weave or to vary its length due to shrinkage variations arising from the mercerizing; and any of these variations occurring along the length of the fabric are compensated for by the take-up or tension roller 44.

In the use of a machine of this character, 25 the object is primarily to scour and wash out from the mercerized fabric all of the caustic alkaline matters and secondarily to provide means for the recovery of the alkaline solution in more or less concentrated condition, whereby it is suitable for immediate 30 use as a mercerizing medium without the necessity of regeneration, this latter being made possible by reason of the fact that the concentrated solution is obtained without 35 being affected by carbonic acid of the atmosphere. While the chamber 2 is open to the atmosphere through the pipes 40, as aforesaid, nevertheless, I am enabled to introduce steam in such quantities that an 40 outward flow of vapors are maintained through said pipes and thereby an inflow of air prevented.

The concentrated alkaline solution overflowing from the well 12 or through a trap 45 may be pumped away for use in the mercerizing machine in any convenient manner, though this feature does not form any part of my invention.

In respect to the washing action of the 50 fluid in the compartments 12^a, it is pointed out that the less concentrated solution flowing from the bottom outlet of the passage 10 meets the fabric passing under the roller 15 and tends to produce an effective washing 55 upon the rising fabric, and similarly, the descending fabric meets a rising fluid current (to the overflow) and hence again insures an effective washing; all of which permits the steaming and rubbing to be followed to be especially effective in displacing 60 the alkaline substance from the fabric.

It will now be apparent that I have devised a novel and useful construction which embodies the features of advantage enumerated 65 as desirable, and while I have in the

present instance shown and described the preferred embodiment thereof which has been found in practice to give satisfactory and reliable results, it is to be understood that I do not restrict myself to the details, 70 as the same are susceptible of modification in various particulars without departing from the spirit or scope of the invention.

Having now described my invention, what I claim as new and desire to secure by Letters Patent is:—

1. In a machine for lixiviating textile fabric, a chamber adapted to provide a heated atmosphere having its lower part in box-like form divided into a series of transverse trough-like compartments separated by a plurality of transverse walls bolted to the bottom and sides of the box-like structure, the upper ends of said transverse division walls being successively at higher elevations and each formed by a double transverse wall with a fluid passage between them, said passage opening in one direction at the bottom into the next lower compartment and opening at the top in the opposite direction into the next higher compartment whereby the fluid from the latter compartment overflows the adjacent wall and downward through the passage to the lower part of the next lower compartment and so on through the series of compartments, submerged guide rollers arranged in said compartments, guide rollers arranged in the upper portion of the enclosed chamber whereby fabric is guided alternately around the submerged rollers and upper guide rolls, means for subjecting the fabric intermediate of said rolls to a scouring action, means to admit washing fluid to the uppermost compartment, and a water seal in the lowermost compartment for permitting the entrance of the fabric while maintaining the compartment in a substantially closed condition.

2. The invention according to claim 1, 110 wherein the bearings for the submerged rollers are formed of wood saturated permanently throughout with a lubricant.

3. The invention according to claim 1, 115 wherein further, the rear wall of the chamber dips into the uppermost compartment to form a water seal and in which further the said end of the machine is provided with a pair of press rolls, levers and counterweights for pressing the upper roller downward upon the lower roller, an adjustable screw connection between the levers and the bearings of the upper press roll, whereby it may be adjusted relatively to the levers, and manually operable cam means for simultaneously lifting the levers for separating the press rolls when inserting the fabric between them.

4. The invention according to claim 1, 120 wherein further, the transverse division

walls between the several compartments are each formed of a unitary casting having front and back plates with a vertical passage between them, the front plate extending to a higher level than the back plate and providing an opening at its bottom for the flow of the fluid from the space between the front and back plates, and means along the bottom of the back plate and the ends of both plates for securing the said wall in the chamber and forming a liquid tight joint along the bottom and ends of the walls.

5. In a machine for lixiviating textile fabric, a chamber having at the bottom a plurality of transverse compartments formed by transverse division walls extending from side to side of the chamber and providing overflow portions at successive higher elevations whereby the washing fluid fed to the highest chamber will overflow into the next and so on throughout the series of compartments, combined with a transverse submerged guide roll in each of the compartments, corresponding guide rolls arranged in the upper part of the chamber, said guide rolls guiding the textile fabric in a zigzag manner through the chamber and the washing fluids in the successive compartments, said fabric entering at the lowermost compartment and leaving at the uppermost one, means for scouring the fabric during its travel through the chamber above the washing compartments, and means within the chamber for applying friction to the opposite surfaces of the fabric and stretching the same laterally from selvage to selvage said means comprising an adjustable frame having a transverse axis and having journaled therein two parallel spirally grooved rolls each having their spirals from the center cut in a right hand manner in one direction and a left hand manner in the other direction, gearing to cause said spiral rolls to revolve in opposite directions, power means to rotate the said spiral rolls, and means for adjusting the frame together with the spiral rolls about its axis for putting more or less frictional contact upon the fabric to suit the 50 character of the same.

6. The invention according to claim 5, wherein further, means are provided for driving the guide rollers which are arranged in the upper part of the enclosed chamber and means driven therefrom for driving the spiral rolls, whereby they are driven at uniform relative speeds with reference to the speed of the guide rolls.

7. The invention according to claim 5, wherein means are provided for rotating the guide rolls in the upper part of the chamber in one direction and the two spiral rolls respectively in opposite direction to each other, and one of said spiral rolls rotating 65 in the same direction as the guide rolls.

8. The invention according to claim 5, wherein further, there is provided perforated pipes for subjecting the fabric on one side while passing through the chamber in a zigzag manner to a scouring fluid medium and also transverse rubbing bars between which bars and perforated pipes the fabric passes, and in which further, similar perforated scouring pipes and rubbing bars are arranged at intervals in the chamber for operating similarly upon the other side of the textile fabric during its zigzag passage through the chamber.

9. The invention according to claim 5, wherein further, means are provided for rotating the guide rolls in the upper part of the chamber in one direction and the two spiral rolls respectively in opposite directions to each other and whereby one of said spiral rolls rotates in the same direction as the guide rolls, and wherein further, the power for operating the spiral rolls is transmitted through a shaft and gearing arranged concentrically with the axis of the frame carrying the spiral rolls and geared to one of said spiral rolls.

10. In a machine for lixiviating textile fabric, a chamber having at the bottom a plurality of transverse compartments formed by transverse division walls extending from side to side of the chamber and providing overflow portions at successive higher elevations whereby the washing fluid fed to the highest chamber will overflow into the next and so on throughout the series of compartments, combined with a transverse submerged guide roll in each of the compartments, corresponding guide rolls arranged in the upper part of the chamber, said guide rolls guiding the textile fabric in a zigzag manner through the chamber and the washing fluids in the successive compartments, said fabric entering at the lowermost compartment and leaving at the uppermost one, means for scouring the fabric during its travel through the chamber above the washing compartments comprising perforated pipes for subjecting the fabric while passing through the chamber in a zigzag manner to a scouring fluid medium and also transverse rubbing bars between which bars and perforated pipes the fabric passes, and in which further, similar perforated scouring pipes and rubbing bars are arranged at intervals in the chamber said bars and pipes arranged for operating similarly upon both sides of the textile fabric during its zigzag passage through the chamber.

11. The invention according to claim 10, wherein further there is provided within the chamber a pair of oppositely rotating spiral rolls for acting upon opposite faces of the fabric to stretch the same preliminary to the action by the scouring means, and adjustable means for varying the extent of 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 action of the spiral rolls upon the fabric.

12. The invention according to claim 10, wherein further, there is provided within the chamber a pair of oppositely rotating spiral rolls for acting upon opposite faces of the fabric to stretch the same preliminary to the action by the scouring means, said spiral rolls provided with adjustable means for varying the extent of their action upon the fabric, and wherein further, there is arranged upon the outside of the machine an additional roll having its outer surface formed with spiral grooves of a right hand construction from the center to one end and of a left hand construction from the center to the other end and over which the fabric is fed for insuring a preliminary stretching thereof in a transverse direction before it enters the washing fluid.

13. The invention according to claim 10, wherein further, means are provided to cause a relative adjustment between the scouring pipes for projecting the fluid and the corresponding bars between which the fabric passes whereby its extent of contact with the said pipes and bars may be adjusted to suit the scouring requirements of the fabric.

14. The invention according to claim 10, wherein further, the chamber is provided on its side walls with large man-holes normally closed by doors hinged at their lower parts and combined with clamping means for holding the doors in closed relation, said man-holes arranged at a level below the feeding and guide rolls in the chamber and above the guide rolls in the transverse fluid compartments.

15. In a machine for lixiviating textile

fabric, a chamber provided at its lower part 40 with transverse washing compartments, guiding means for guiding the fabric in a zigzag manner through the chamber and the fluid in the washing compartments, pressure rolls at one end of the chamber for 45 subjecting the fabric to pressure upon leaving the washing fluid, means adjacent to the other end of the chamber for stretching the fabric in a transverse direction, and means for guiding the fabric to the chamber and 50 the stretching means under uniform tension which comprises two guide rolls in fixed bearings, an adjustable guide roll movable in vertically adjustable bearings and for drawing the fabric downward between the 55 fixedly positioned guide rolls, counter-balancing means for the movable guide roll to regulate the amount of tension put upon the fabric, a pinion at each end of the movable guide roll and vertical racks with which the 60 pinions mesh to insure the movable roll moving to equal extents at opposite ends so that it shall at all times operate in parallel relation to the aforesaid guide rolls from which it receives and to which it delivers 65 the fabric.

16. The invention according to claim 15, wherein further one of the rollers supported in fixed bearings is positively driven to feed the fabric, and the tension roll is free to 70 rotate on a transverse shaft journaled in the adjustable bearings and having the pinions secured near its ends, whereby said shaft always remains horizontal while being raised or lowered.

In testimony of which invention, I hereunto set my hand.

CHARLES H. ELLIOTT.
